US00D753781S

(12) **United States Design Patent**
Cauley, Jr. et al.

(10) **Patent No.:** **US D753,781 S**
(45) **Date of Patent:** **** Apr. 12, 2016**

(54) **FIREARM MAGAZINE LOADER**

(71) Applicant: **Battenfeld Technologies, Inc.**,
Columbia, MO (US)

(72) Inventors: **Dennis W. Cauley, Jr.**, Booneville, MO
(US); **Michael Poehlman**, Columbia,
MO (US); **Adam J. Birk**, Hallsville, MO
(US); **James Gianladis**, Harrisburg, MO
(US); **Matthew Kinamore**, Columbia,
MO (US)

(73) Assignee: **Battenfeld Technologies, Inc.**,
Columbia, MO (US)

(**) Term: **14 Years**

(21) Appl. No.: **29/495,091**

(22) Filed: **Jun. 26, 2014**

(57) **CLAIM**

The ornamental design for a firearm magazine loader, as shown and described.

DESCRIPTION

FIG. 1 is a front perspective of a first embodiment of a firearm magazine loader of our new design;
FIG. 2 is a front elevation of the firearm magazine loader;
FIG. 3 is a top view of the firearm magazine loader;
FIG. 4 is a right side elevation of the firearm magazine loader;
FIG. 5 is a rear elevation of the firearm magazine loader;
FIG. 6 is a bottom view of the firearm magazine loader; and,
FIG. 7 is a left side elevation of the firearm magazine loader. Features forming no part of the claimed design are illustrated in broken lines.

1 Claim, 7 Drawing Sheets
